US00D977016S

(12) **United States Design Patent** (10) **Patent No.:** **US D977,016 S**
(45) **Date of Patent:** **** Jan. 31, 2023**

(54) **MAGNETIC BALL**

(71) Applicant: **Xiufu Luo**, Guangdong (CN)

(72) Inventor: **Xiufu Luo**, Guangdong (CN)

(**) Term: **15 Years**

(21) Appl. No.: **29/833,942**

(22) Filed: **Apr. 8, 2022**

(51) **LOC (14) Cl.** **21-01**

(52) **U.S. Cl.**

USPC **D21/404; D21/455**

(58) **Field of Classification Search**

(57) **CLAIM**

The ornamental design for a magnetic ball, as shown and described.

DESCRIPTION

FIG. 1 is a perspective view of the magnetic ball showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
